MINE SHUTTLE CAR

John D. Russell, Bradford Woods, and Paul R. Johnson,
Franklin, Pa., assignors to Joy Manufacturing Company,
Pittsburgh, Pa., a corporation of Pennsylvania

Application May 16, 1958, Serial No. 50,923

Term of patent 14 years

(Cl. D14—3)

FIG. 1.

FIG. 2.

Des 185,174

PAGE 2

FIG. 3.

FIG. 4.

FIG. 5.

Figure 1 is a side view of a mine shuttle car embodying our invention.

Figure 2 is a side view looking at the mine shuttle car from its opposite side.

Figure 3 is a perspective view of the mine shuttle car showing the rear and one side of the car.

Figure 4 is a perspective view showing the front and the other side of the mine shuttle car.

Figure 5 is a rear perspective view of the mine shuttle car.

We claim:

The ornamental design for a mine shuttle car, as shown.
